POWER DIVISION IN ELECTROMECHANICAL SYSTEMS

David Grimes, Beverly, N. J., assignor, by mesne assignments, to Philco Radio and Television Corporation, Philadelphia, Pa., a corporation of Delaware

Application August 19, 1939, Serial No. 291,093
In Great Britain August 26, 1938

10 Claims. (CL. 179—1)

This invention relates to electromechanical systems and power considerations therein, and has for its general object to provide an optimum division of power between various sections of such a system in order that the maximum efficiency or output power may be derived therefrom with a minimum of expense.

The invention applies particularly to electrodynamic sound reproducing apparatus wherein a vibratory or to-and-fro motion of a moving system is obtained by means of electric and/or magnetic forces existing between a conductor on the moving system and a stationary field structure, and wherein the moving system is supplied with energy from one or more power output tubes, preferably operating as Class A amplifiers.

One of the well known applications of such a system is to be found in audio amplifiers and loudspeakers as used in public address systems, radio receiving sets, and the like, where a large portion of the total power available and supplied by a power supply unit is divided between two important loads, namely, the loudspeaker field winding and the power output tubes. Now the total power available is usually restricted due to economic and practical considerations, and it is, therefore, of importance, as disclosed herein, that a proper balance of power consumption be arrived at for these loads.

Accordingly, by the present invention there is provided in an electromechanical system, an electrodynamic loudspeaker having a magnetic field structure, a field winding, and a moving system; vacuum tube power amplifier means for supplying said moving system with energy whereby it is caused to move relative to said field structure; and a power supply means for supplying power to said field winding and to the plate circuit of said amplifier means, characterized in that the power supplied to said plate circuit is comparable to the power supplied to said field winding.

Returning to the illustration of the audio amplifier and loudspeaker; and assuming linearity throughout, it has been found experimentally that where the total available power is limited, maximum output power may be derived from the system when the power supplied to the loudspeaker field is equal to the power supplied to the tube or tubes in the power output stage, and this is true no matter what the relative efficiencies of the loudspeaker or output tubes may be. When the power division between speaker field and output stage is unequal, a loss in acoustic output power is found to result, and this loss increases more rapidly as the degree of mismatch is increased. Thus while small mismatches may not result in serious losses in acoustic power output, a four-to-one mismatch may result in a 36% loss, while an eight-to-one mismatch may result in a 60% loss.

The same conclusions may be arrived at analytically. Thus assuming that the magnetic circuit of the loudspeaker field structure is operating below saturation, i. e., that the flux varies substantially linearly with field current, it may be shown that if the power W_f supplied to the speaker field be the only variable, then the acoustic power W_a will vary directly with W_f . Similarly, if the power output tubes be operated on a linear portion of their characteristic, it may further be shown that W_a will likewise vary linearly with the power W_o supplied to the plate circuit of the output stage; or it may be stated that the acoustic power W_a is directly proportional to the product $W_f \times W_o$. Assuming then, as is normally the case, that the total power, $W_f + W_o$, available to be divided between field and output stage, is limited, then the product $W_f \times W_o$ will be the maximum when $W_f = W_o$. Thus by dividing a limited source of power equally between the loudspeaker field winding and the plate circuit of the power output tube or tubes, the maximum possible acoustic power output may be obtained. Conversely, assuming that a specified acoustic power output is required, this may be achieved with maximum economy in the design of the power supply unit when the power is divided as hereinbefore disclosed. It has been found that where mismatches of 5 to 1 or more have been made (and even more serious mismatches are not at all uncommon) the practice of the present invention will make possible either a considerable saving in the cost of the power supply circuit, or, conversely, will considerably increase the acoustic power output which the speaker can deliver.

It is, therefore, an important object of this invention so to utilize a limited power supply source, such as is employed in conjunction with a radio receiver or the like, as to derive the maximum sound output level from the sound system of said receiver.

Another object of this invention is to disclose the optimum ratio of the powers supplied to the anode circuit of a Class A output stage and to the field windings of a moving coil loudspeaker.

The invention, as well as other objects thereof, may best be understood by reference to the following description and to the accompanying drawing, in which—

Fig. 1 is a schematic diagram representative of one embodiment of the invention;

Fig. 2 is a schematic diagram of an alternative embodiment of the invention; and

Fig. 3 is a curve showing the relation between acoustic power output and the ratio W_o/W_f .

In Fig. 1 there is schematically shown a portion of a radio receiver which may comprise the usual carrier frequency amplifier and detector circuits (represented generally by the rectangle 1), an

audio output stage employing a vacuum tube V_3 , an output transformer 5 , a loudspeaker L. S. having a moving coil 6 , and a power supply source which comprises the power transformer 2 , rectifier tube V_4 , and a filter system which may include the series choke F , and the shunt capacitors 3 and 4 .

Since the details of the circuits employed in the amplifier-detector portion of the receiver 1 , are of no special interest as regards this invention, they have been indicated merely by the triodes V_1 and V_2 , and by the dotted plate circuit representations 7 . In the interests of simplicity, there is shown a single pentode power output tube V_3 . However, if desired, two such pentodes, or alternatively, a pair of triodes, may be employed in a push-pull output arrangement.

With reference to the power supply system, the choke F may serve both as the field winding and field structure for the loudspeaker L. S., and as a series-connected choke coil in the filter circuit. The design and construction of electrodynamic loudspeakers of this general type, in which a voice coil is affixed to a sound radiator or diaphragm, and arranged to move in a magnetic field set up by the speaker field F , is well known and requires no further description. The anode circuits of the tubes V_1 and V_2 may be supplied from either the input or output side of the choke F , but preferably from the latter. According to the invention, the winding comprising the field winding F is so designed that the power expended in said winding is comparable to the power supplied to the output tube V_3 . Conversely, it is possible to adopt a given field winding F and to choose an output tube or tubes V_3 such that the above-mentioned relation is again obtained. The power dissipated in the field winding F depends in general upon the size and kind of wire adopted, upon the number of turns, and upon the mean length of wire per turn.

Fig. 2 represents a modification of the circuits of Fig. 1. Corresponding circuit elements, however, have been given like designations in both figures. In Fig. 2 there is provided a two-section filter, the first section of which includes the series choke coil C , and the second section of which includes the winding F of the speaker field. Three electrolytic capacitors 3 , 4 and 10 may be provided as indicated. It will be observed that, with respect to the plate circuits of the tubes V_1 and V_2 which are connected to the point $B+$, the windings C and F are serially connected between the cathode of the rectifier V_4 and the leads 7 . However, with respect to the output stage, it may be observed that the field winding F (serially connected with the resistor 9) is connected in shunt with the plate circuit of the tube V_3 . This results from the fact that the plate voltage for V_3 is derived from the point $B++$ between the windings C and F . If desired, a tapped resistor 8 may be included as shown to provide a bias voltage supply for uses which are well understood in the art. In the embodiment of Fig. 2, the combination of the field winding F and the resistor 9 should be so designed as to provide the desired voltage $B+$ for the tubes V_1 and V_2 while simultaneously providing the desired division of power between the field winding F and the plate circuit of the tube V_3 .

In either of the illustrated embodiments, the final output stage preferably employs tubes operating as Class A amplifiers. Under these conditions, the balance of power between the output stage and the speaker field will be sub-

stantially fixed, and independent of the amplitude of signals within the rated capacity of the output stage. Where Class B amplifiers are employed, the desired balance of power could in general be achieved only at a particular audio signal level, preferably at a high signal level.

Reference is now directed to Fig. 3 in which relative acoustic output power, W_A , is shown as a function of the ratio W_0/W_1 , i. e. the ratio of the power supplied to the plate circuit of the output stage to the power supplied to the loudspeaker field winding. The total power W_0+W_1 is held constant. It will be observed that maximum acoustic output is obtained when the ratio W_0/W_1 is unity. Similarly it may be seen that the loss in relative acoustic output, as the ratio W_0/W_1 departs from unity, is the same for either the said ratio or for its inverse. Thus, for example, acoustic output falls to about 64% of its maximum value at ratios of both 4 and $\frac{1}{4}$. For this reason the curve, as plotted, is symmetrical about unity, i. e. about the ratio 1 to 1 . It will be seen from the curve that a mismatch of $\frac{1}{2}$ to 1 results in only about 18% power loss.

The manner in which the present invention may be practiced to yield a substantial saving in power supply costs may be seen from the following illustration. Assume that it is desired to provide a certain maximum sound output level, and that this can be obtained, in accordance with the prior art, by means of a 3 watt speaker field and a power output stage whose plate circuit is supplied with 12 watts of power; that is, a total of 15 watts for the speaker field and output stage plate circuit. In accordance with the present invention, the same sound output may be obtained by supplying 6 watts to the speaker field and 6 watts to the output stage, the product of 3 and 12 being equal to 6 squared, or 36. Thus, in each case the product W_1+W_0 is equal to 36, and hence the acoustic outputs of the two systems are alike. In the latter case, however, only a total of 12 watts need be supplied to the speaker field and output stage, as compared to the 15 watts required in the former case. In the mass production of radio receivers, this difference represents a substantial saving in the cost of power supply and associated circuits.

Similarly, in the example cited, the output stage of the balanced system may employ a tube or tubes of only one-half the power rating of those required in the unbalanced system of the prior art, in this instance 6 watts as compared to 12 watts. This, obviously, represents an important saving in tube costs.

Obviously, the optimum division of power taught by this invention may be secured by means of various circuit arrangements other than those illustrated in the accompanying drawing, which have been included merely as examples for the purpose of disclosure. Similarly the invention is not to be limited to equal or highly precise divisions of power between the loudspeaker field winding and the plate circuit of the output tube or tubes. For example, it is deemed that mismatches of the order of 2 to 1, or 1 to 2 fall well within the sphere of this invention. Where such mismatches obtain, it is deemed that the power supplied to the loudspeaker field winding and that supplied to the plate circuit of the output tube or tubes are comparable one to the other, particularly when considered with reference to the relatively great mismatches hereinbefore mentioned.

I claim:

1. In an audio frequency output system, an

electrodynamic loudspeaker having a field structure, a field winding wound on said field structure to provide a magnetomotive force therefor, a moving system having a coil arranged to lie in an air-gap in said field structure, vacuum tube power amplifier means for supplying said coil with audio frequency energy, a power supply source having a certain amount of power available for said vacuum tube amplifier and said field winding, means for supplying the plate circuit of said amplifier with substantially half of said available power, and means for supplying said field winding with the remaining part of said available power, thereby to render the acoustic output of said loudspeaker substantially a maximum.

2. In a radio receiver or the like, a plurality of vacuum tube amplifiers, a vacuum tube power output stage, a loudspeaker having a voice coil and a magnetic field structure, a field winding associated with said field structure, a power source having a limited maximum power output, connections between said power source and said vacuum tube amplifiers for supplying said amplifiers with a part of the maximum output of said power source, connections for supplying substantially half of the remainder of said maximum output to said power output stage, and connections for supplying the other half of said remainder to said field winding, thereby to render the acoustic output of said loudspeaker substantially a maximum.

3. In an audio frequency output system, an electrodynamic loudspeaker having a field structure, a field winding, and a moving system, class A vacuum tube amplifier means for supplying said moving system with energy, and a power supply means for supplying power to said field winding and to the plate circuit of said amplifier means, characterized in that the power supplied to said plate circuit is substantially equal to the power supplied to said field winding, thereby to render the acoustic output of said loudspeaker substantially a maximum.

4. In a radio receiver or the like, a plurality of vacuum tube amplifiers, a vacuum tube power output stage operating as a class A amplifier, a loudspeaker having a voice coil and a magnetic field structure, a field winding associated with said field structure, a power source having a limited maximum power output, connections between said power source and said vacuum tube amplifiers for supplying said amplifiers with a part of the maximum output of said power source, connections for supplying substantially half of the remainder of said maximum output to said power output stage, and connections for supplying the other half of said remainder to said field winding, thereby to render the acoustic output of said loudspeaker substantially a maximum.

5. In an audio frequency output system, an electrodynamic loudspeaker having a field structure and a field winding wound on said structure, a moving coil arranged to lie in an air gap in said field structure, a vacuum tube power amplifier for supplying said moving coil with power at an audio frequency rate, a power supply source, said source having only a limited amount of power available for said power amplifier and said field winding, a path including said field winding for supplying substantially half of said available

power to the plate circuit of said power amplifier, said field winding having such a resistance that the other half of said limited available power is dissipated in said field winding and structure, thereby to render the acoustic output of said loudspeaker substantially a maximum.

6. In an audio frequency output system, a series circuit including a loudspeaker field winding and the plate circuit of a class A vacuum tube power output stage, and means for supplying said series circuit with electrical power, said means having only a limited available power output, said system being characterized in that said limited available power is divided substantially equally between said field winding and said plate circuit, thereby to render the acoustic output of said loudspeaker substantially a maximum.

7. In an audio frequency output system, a circuit including in parallel a loudspeaker field winding and the plate circuit of a vacuum tube power output stage, said output stage supplying audio power to a moving system of said loudspeaker, means for supplying said parallel circuit with electrical power, said means having only a limited available power output, said output system being characterized in that said available power is divided substantially equally between said field winding and said vacuum tube plate circuit whereby the maximum efficiency is obtained from said system.

8. In an audio frequency output system, a circuit including in parallel a loudspeaker field winding and the plate circuit of a vacuum tube power output stage, said output stage being of the class A type and adapted to supply audio power to the moving system of said loudspeaker, means for supplying said parallel circuit with electrical power, said means having only a limited available power output, said output system being characterized in that said available power is divided substantially equally between said field winding and said vacuum tube plate circuit whereby the maximum efficiency is obtained from said system.

9. In an audio frequency output system, an electrodynamic loudspeaker having a field structure, a field winding, and a moving system, vacuum tube amplifier means for supplying said moving system with energy, and a power supply means for supplying power to said field winding and to the plate circuit of said amplifier means, characterized in that the ratio of the power supplied the anode circuit of the output stage to the power supplied said field winding is not less than 0.4 nor greater than 2.5.

10. In a radio receiver or the like, a plurality of vacuum tube amplifiers, a vacuum tube power output stage, a loudspeaker having a voice coil and a magnetic field structure, a field winding associated with said field structure, a power source having a certain rated power output, circuits for supplying said amplifiers with a portion of said rated output, circuits for supplying said power output stage with another portion of said rated output, and circuits for supplying said field winding with the remainder of said rated output, said receiver being characterized in that the ratio of the power supplied the anode circuit of the output stage to the power supplied said field winding is not less than 0.4 nor greater than 2.5.
